PACKER FOR FLAKE MATERIAL
Guthrie B. Stone, ½ Stone Conveyor Co. Inc.,
Honeoye, N.Y.

Filed Oct. 15, 1959, Ser. No. 846,617
7 Claims. (Cl. 141—73)

The present invention generally relates to a packing device for filling containers and is primarily concerned with packing flakes or flake material or similar material having a relatively low density into a container such as a can.

The present invention incorporates a structure for forcing or packing flakes of two or three times the volume of the container into the container with a minimum damage to the flakes and requiring only a minimum of labor.

The primary object of the present invention is to provide a flake packing machine which is primarily for the purpose of packing flake material such as dehydrated potato flakes into a can with the volume of flakes being from two to three times the volume of the can whereby the flakes may be economically distributed.

Another object of the present invention is to provide a packing machine which incorporates an elongated flake receiving barrel having a ram therein which receives a predetermined weight of flakes from a suitable weighing machine after which a can is brought into position tightly against the bottom of the barrel and the ram is forced downwardly for forcing the flakes into the can and subsequently returned to a start position with there being also a mechanism for ejecting the filled can to a suitable can sealing machine. The ejection of the filled can is accomplished by a piston and cylinder arrangement which will actuate the feed mechanism for placing a new can in position when the ejector returns to a start position with their being a safety switch for preventing operation of the machine unless the can is properly orientated in relation to the rest of the structure.

Other objects of the present invention will reside in its simplicity of construction, ease of operation, efficiency, accuracy, adaptation to its particular purposes and its relatively inexpensive manufacturing cost.

These together with other objects and advantages which will become subsequently apparent reside in the details of construction and operation as more fully hereinafter described and claimed, reference being had to the accompanying drawings forming a part hereof, wherein like numerals refer to like parts throughout, and in which:

FIGURE 1 is a perspective view of the flake packing machine with portions broken away and illustrating the can receiving platform and the lower end of the barrel together with the piston and cylinder arrangement for moving a can into position, raising the can against the barrel and subsequently ejecting the can;

FIGURE 2 is a side elevational view of the machine with a portion of the top part of the ram being broken away;

FIGURE 3 is a plan view of the machine with the barrel and ram mechanism being broken away;

FIGURE 4 is a detailed sectional view taken transversely along the plane just above the magnet for holding the cans;

FIGURE 5 is a detailed side elevational view illustrating the connection between the barrel and ram device;

FIGURE 6 is a detailed sectional view taken substantially upon a plane passing along section line 6—6 of FIGURE 5 illustrating the lower end of the ram;

FIGURE 7 is a detailed sectional view taken substantially upon a plane passing along section line 7—7 of FIGURE 5 illustrating the construction of the upper end of the barrel and particularly the chute for receiving the flakes;

2

FIGURE 8 is a transverse, sectional view of the barrel illustrating the construction of the plunger therein; and

FIGURE 9 is a schematic wiring diagram of the machine illustrating the various switches for operating the structural mechanism.

Referring now specifically to the drawings, the numeral 10 generally designates the flake packing machine of the present invention which is supported on a generally table top-like member 12 supported by a plurality of legs 14. 10 Extending vertically upwardly from one side portion of the table top 12 is a barrel generally designated by numeral 16 with their being a pneumatically or fluid pressure operated ram 18 disposed above the barrel 16 and in longitudinal alignment therewith. The barrel 16 is in the 15 form of an elongated cylindrical tubular member 20 which is rigidly supported in position by brace members 22. As illustrated in FIGURE 1, the barrel 16 is adjustable in relation to the brace members 22 by virtue of mounting lugs 24 extending alongside of a brace member 22 and 20 being secured thereto by bolts 26. The lower edge of the lug 24 is provided with a projection 28 engageable by an elevating screw 30 which is in screw-threaded engagement with a lug 32 affixed to the brace 22. The lug 24 is provided with slots 34 receiving the bolts 26 for permitting 25 adjustment thereof.

Adjacent the upper end of the barrel 16, there is provided a laterally extending hopper or chute 36 which has an open upper end 38 for receiving flakes from a weighing machine (not shown) which weighing machine is not 30 part of the present invention. Disposed above and engaged with the upper edge of the hopper 38 is a flange 40 which receives fastening members 42 extending through a flange 44 on the lower end of the cylinder 46 which forms part of the ram 18 whereby adjustment of the bolts 35 42 may effect vertical adjustment of and alignment of the ram 18 with the longitudinal axis of the barrel 20. A piston rod 48 extends downwardly from the ram 46 into the barrel and has a plunger 50 connected thereto. The plunger 50 is provided with a plurality of apertures 52 for 40 permitting escape of air and is preferably constructed of a plastic material having sufficient rigidity to compress the flake material without the flakes adhering to the plunger 50 which acts as a piston to move and compress the flakes disposed within the barrel 16.

The lower end of the barrel 16 is open and a can receiving and holding plate of a circular configuration is disposed below the lower end of the barrel 16 and receives a tin can 56 thereon. Disposed below the table top member 12 is a piston and cylinder arrangement with the cylinder being designated by numeral 58 and having a piston rod 60 extending up through the table top member 12 and rigidly secured to the platform 54 so that the tin can 56 may be brought into tight contacting engagement with the lower end of the barrel 16. A safety switch 55 actuating member 62 is disposed in the brace member 22 in the path of movement of the can 56 so that the switch actuating member 62 will not be actuated unless the can 56 is properly positioned on the platform 54. A permanent magnet 64 is provided in a slot 66 in the brace 22 for positioning and holding the can 56 in position. The 60 magnet 64 may be insulated in any manner desired.

Extending laterally from the platform 54 is a can supply guide or chute generally designated by numeral 68 which includes a plurality of rods 70 arranged in such a manner to provide an inclined gravity chute for a plurality of cans which may receive the cans in a vertical position as they proceed downwardly. A vertical stop rod 72 is provided for limiting the movement of the cans 56 for positioning the cans on a stationary platform 74 immediately before they are pushed onto the platform 54 with their being a piston and cylinder arrangement with the cylinder being designated by numeral 70

78 disposed with the longitudinal axis in alignment with the center of the platform 54. The outer end of the piston rod 80 is provided with an adapter 82 curved to conform to the can 56. Thus, when the piston rod 80 is extended, the adapter 82 will engage the can 56 and move the can off of the platform 74 onto the platform 54 and when the piston rod 80 is retracted, the next adjacent can 56 will move down to engage the stop rod 72 or the transverse stop rod 84.

Disposed behind the platform 54 is a piston and cylinder arrangement with the cylinder being designated by the numeral 86 and with the piston rod 88 having an arcuately curved adapter 90 thereon which is adapted to engage a can 56 when it is to be ejected from the platform 54. A plurality of horizontal rods 92 are provided and are secured to a U-shaped support 94 which can receive some type of conveyor for conveying the filled packed cans to a sealing machine.

The entrance to the platform 54 is provided with a spring urged gate member 96 pivotally supported on a sleeve 98 carried by the vertical rod 70 and limited by a projecting finger 100 which engages an inverted U-shaped frame member 102. The spring 104 urges the gate member 96 into the path of movement of the cans 56 as they proceed onto the platform 54 thus assuring that only one can will move into position.

The various piston and cylinder arrangements are preferably pneumatically operated although they may be operated by other fluid pressure and various switch mechanisms are employed for controlling the operation of the components with each of the piston and cylinder arrangements being solenoid valve controlled.

FIGURE 9 illustrates schematically the wiring diagram for control of the operation with the entire apparatus being connected to line voltage from any suitable source of supply. Switch 106 is a micro-switch which is the can orientation switch. The can orientation micro-switch 106 is connected in a line and is in series with the feed cylinder solenoid 108 which will cause the feeding of a can into the area above platform 54 if the ejection cylinder micro-switch 110 is closed which occurs when the ejection cylinder has returned to a normal position. A micro-switch 112 in series with the lower cylinder release solenoid 114 and the ejector cylinder solenoid 116 so that when the micro-switch 112 is closed which occurs when the press ram or cylinder returns to its upper position, the platform 54 will lower and the discharge cylinder will eject a filled can. The can positioning switch 118 is provided with the actuating arm 62 and is in series with the solenoid 120 for causing the elevating cylinder connected with the platform 54 to elevate the can 56 when the switch 118 is closed. Also, the press or ram solenoid 122 will be operated thus causing the plunger to descend if the switch 124 is closed which switch 124 may be a micro-switch disposed in the path of movement of the platform dumping gate which will close the switch 124 when a predetermined weight has been obtained and is dumped into the hopper. Thus when the scales dump the material into the hopper, the switch 124 will close and since a can is in position and engages the finger or arm 62, the switch 118 will close thus energizing the solenoids 120 and 122 causing the platform 54 to elevate and causing the ram to move downwardly for compressing and compacting the flakes. The ram will then return to its upper position and cause switch 112 to be closed and switch 124 to be opened since the scales have moved to a neutral position. The piston and cylinder arrangement 58 will then lower the platform 54 and the ejection piston and cylinder arrangement will eject the filled container. As the ejection piston and cylinder arrangement returns to its normal position, the switch 110 will be closed and with the switch 106 being closed due to the orientation of the open upper end of the container facing upwardly, the solenoid 108 will be energized thus causing the feed cylinder 78 to

project a can into the area above the platform 54 so that when the switch 118 is closed by the can, the device will automatically operate in another sequence of events when the scale platform dump gate closes the switch 124.

5 In operation, the barrel receives the flakes from the weighing machine which dumps when a pre-set weight has been reached. The switch 124 is thus closed which causes the solenoid valve to be energized and forces the bottom cylinder to act upwardly thus bringing the can into position tightly engaging the bottom of the barrel. At the same time the top air cylinder starts the ram downward and forces the flakes into the can and returns to its start position. In doing so, it trips the micro-switch 112 which causes the discharge or ejector air cylinder to act at the same time forcing the can outward to a can sealer. When the ejector cylinder retracts to its start position, it also causes the loading cylinder to act to place a new can in position. A switch 118 is placed where the can, when in proper position contacts its operating lever 119 so that the machine will not operate unless the lever 119 is not engaged with a bottom of an inverted can. This switch is in the top of the gravity fed chute for empty cans and if actuated because a can is in upside down or bottom up position, the loading air cylinder will be rendered inoperative. Thus, the operation of the machine will be substantially automatic if the weighing machine will operate switch 124 and will discharge into the hopper sequential weighed quantities of flake material.

10 20 25 30 35 40 45 50 55 60 65

The foregoing is considered as illustrative only of the principles of the invention. Further, since numerous modifications and changes will readily occur to those skilled in the art, it is not desired to limit the invention to the exact construction and operation shown and described, and accordingly all suitable modifications and equivalents may be resorted to, falling within the scope of the invention as claimed.

What is claimed as new is as follows:

1. A flake packing machine for compressing and packing flake material into a container of substantially rigid construction comprising an elongated barrel, means for supporting said barrel in vertical position, hopper means at the upper end of the barrel for receiving a predetermined quantity of flake material, a ram connected with the upper end of the barrel and including a plunger vertically movably disposed in the barrel for forcing the flake material downwardly through the barrel, a platform disposed below the barrel and in alignment therewith for receiving a container, said platform being elevatable for bringing the open upper end of the container into engagement with the barrel whereby the flakes compressed by the ram will be compressed into the container, a feed chute communicating with the platform for positioning containers adjacent thereto, means for moving a container from the chute onto the platform, means separate from said means for moving a container onto the platform for ejecting a filled container off of the platform, and means for raising and lowering said platform, all of said means being switch controlled, the means for moving the container onto the platform being responsive to retraction of the container ejecting means and positioning of the ram in its uppermost position, the downward movement of the ram being controlled by the position of the container, and the ejecting means being controlled by the position of the ram when it returns to a start position.
2. The structure as defined in claim 1 wherein each of said means includes a fluid pressure operated piston and cylinder arrangement controlled by solenoid valves.
3. The structure as defined in claim 2 wherein said containers are of metallic construction of ferrous material, and a permanent magnet for holding the container in position on the platform while being engaged with the lower end of the barrel.
4. The structure as defined in claim 2 wherein said barrel supporting means includes a vertically adjustable

connection with the barrel for varying the degree of compaction of the flake material.

5. The structure as defined in claim 1 wherein a spring urged gate is provided on the chute for closing the entrance to the platform thereby assuring that only a single container will be placed on the platform.

6. The structure as defined in claim 1 wherein said plunger is provided with a plurality of apertures for passage of air for facilitating the downward movement thereof within the barrel.

7. A flake packing machine for compressing and packing flake material into a container of substantially rigid construction comprising an elongated barrel, means for supporting said barrel in vertical position, hopper means at the upper end of the barrel for receiving a predetermined quantity of flake material, a ram mechanism connected with the upper end of the barrel including a plunger vertically movably disposed in the barrel for forcing the flake material downwardly through the barrel, a platform disposed below the barrel and in alignment therewith for receiving a container, said platform being elevatable for bringing the open end of the container into engagement with the barrel whereby the flakes compressed by the ram will be compressed into the container, a feed chute communicating with the platform for positioning containers adjacent thereto, means for mov-

ing a container from the chute onto the platform, means for pushing a filled container off of the platform, said means for moving said container onto the platform and said means for pushing said filled container off of the platform operating perpendicularly in a plane parallel to the surface of the platform, and means for raising and lowering said platform, all of said means being switch controlled.
